UNITED STATES PATENT OFFICE.

FORREST L. CANTRALL, OF ALTURAS, CALIFORNIA.

OILER.

1,326,845.

Specification of Letters Patent.

Patented Dec. 30, 1919.

Application filed June 8, 1918. Serial No. 238,837.

To all whom it may concern:

Be it known that I, FORREST L. CANTRALL, a citizen of the United States, and a resident of Alturas, county of Modoc, and State of California, have invented a new and useful Oiler, of which the following is a specification.

My invention relates to oil cans, and one of the objects of the invention is to provide 10 a self filling oil can.

Another object of the invention is to provide an oil can which will not leak.

The invention possesses many other features of advantage, some of which, with the 15 foregoing, will be set forth in the following description of the preferred form of my invention which is illustrated in the drawings accompanying and forming part of the specification. It is to be understood that 20 I do not limit myself to the showing made by the said drawings and description, as I may adopt variations of the preferred form within the scope of my invention as set forth in the claims.

25 Referring to the drawings:

Figure 1 is a vertical section through the center of the oiler.

Fig. 2 is a modified form of the oiler of my invention.

30 Broadly, my invention comprises a closed casing formed of telescopic sections. Means are provided for extending said casing so that the suction thus produced will draw oil into the casing, and means are also provided for sealing the outlet passage when 35 the casings are extended so that all leakage is prevented even though the oiler lies upon its side.

The oiler of my invention consists of a 40 lower section 2 adapted to hold a quantity of oil. Arranged in the section 2 is a piston 3, fixed upon the lower end of a tube 4. The end of the tube is reduced in diameter to form a shoulder 6 and a metallic washer

45 7 is disposed on each side of the piston. Leather washers 8 are disposed between the washers 7 and the piston 3, and washers and piston are held tightly on the tube by upsetting or expanding the lower edge 11 of 50 the tube. The outer edge of each leather washer is formed into a flange 12 which forms a tight working fit with the sides of the casing section 2. The function of the metal washers is to hold the leather washers 55 in position, and the leather washers prevent leakage past the piston.

The upper end of the tube 4 is threaded and adapted to receive the socket 14 of the spout 16. A valve seat 17 is rigidly fixed in the lower end of the tube and a valve 18 formed by the enlarged end of the rod 19 fixed to the bottom of the section 2 is adapted to close the passage into the tube, when the piston has risen sufficiently to seat the valve. Preferably the top of the valve 18 is provided with a notch to fit a screw driver, and the lower end of the rod is threaded to engage a boss 20 formed in the bottom 21 of section 2. A compression spring 22 in the tube 4 lying between the 70 socket 14 and the top of the fixed valve 18 tends to keep the piston 3 in its highest position in the section 2. In this position the valve 18 engages the seat 17 and closes the outlet passage therethrough, and also 75 limits the upward movement of the piston 3.

Rigidly secured to the upper part of the tube and extending downwardly about the section 2 is an upper casing section 23 adapted to telescope upon the lower section 2 80 when the piston 3 moves downwardly in the latter section. The function of the section 23 is to incase and protect the tube 4 and piston 3 and to form with the lower section a closed casing convenient to handle and 85 operate.

From the above, it will be clear that the oiler may be held in one hand and by pressing the upper and lower sections together, the valve is opened and the contents of the 90 oil chamber 24 discharged through the tube 4 and spout. Releasing the hold upon the upper section, the spring 22 raises the piston and upper section and closes the valve so that the contents of the oil chamber cannot 95 discharge no matter what the position of the oiler is. Obviously, if the open end of the spout is inserted into a body of oil, such recovery of the piston will fill the oil chamber.

100 Preferably an intermediate telescopic casing section 26 is inserted between the upper and lower sections so that the full capacity of the lower section may be utilized, and to provide a larger engaging surface so that 105 jamming of the sections upon each other is avoided.

Means are provided for retaining the intermediate section in proper relation to the other two sections. The wall of the intermediate section is turned inwardly and downwardly to form a cup 27, having an 110

aperture in the bottom thereof through which the tube 4 passes. The proportions of the parts are such that with the piston in the lowest position in the lower section, the 5 bottom edges 28 and 29 of the two sections 23 and 26 respectively lie in the plane of the bottom 21 of the lower section, the bottom 31 of the cup lying above the piston about midway between the extreme lower 10 and upper positions of the latter. As the piston and upper section 23 rise, the piston engages the cup and carries the section 26 upwardly for the remaining half of its stroke, positioning the parts finally as shown 15 in Fig. 1, the intermediate section engaging about one half of each of the other two sections. In order to prevent an upward displacement of the intermediate section, a coil spring 32 is disposed about the outside of 20 the tube 4 and between the bottom 31 of the cup and the upper wall 33 of the section 23. The intermediate section therefore cannot be displaced downwardly because of the engagement of the cup with the piston, 25 and the spring 32 resists upward displacement. The result is a smooth telescopic action between the casing sections, which tend to extend into the position shown in Fig. 1.

In Fig. 2, I have shown a structure in 30 which the upper casing is also an oil reservoir, thus increasing the capacity of the oiler with no increase in size.

The piston 3 is secured upon a tube 36, the top of which is threaded tightly into the 35 bell shaped projection 37 formed upon the top of the upper casing section 23. The tube 4 in which a valve seat 17 is arranged as already explained is rigidly fixed to the bell 37 and lies within the tube 36. At its lower 40 end it is fixed to the tube 36 and to the piston 3 by the spokes 38 leaving a passage between the two tubes opening on the under side of the piston. The outer tube 36 is provided with apertures 39, thus placing the 45 chamber 24 in the lower section in communication with the chamber 40 in the upper section.

The top wall 41 of the intermediate section 26 is formed as a piston to work in the 50 upper section and a tight working fit between this piston and the walls of the section and the tube 36 is secured by an annular flanged leather washer 42 held in place by an annular metallic washer 43 suitably 55 secured by screws 44.

An annular stop 46 fixed on the tube 36 enables the upper section 23 and the piston 3 to pick up and move the intermediate section when the sections are extending and 60 the position of the stop is such that it engages the piston 41 about midway of the stroke of the piston 3. The spring 47 performs the same function as the spring 32 in Fig. 1 construction, *i. e.*, it prevents the upward displacement of the intermediate sec-

tion. The upper end of the spring 47 is disposed within the bell 37 which is formed large enough to accommodate the compressed coils of the spring when the piston 41 is in its highest position against the top wall 33 70 of the upper section.

With the sections telescoped upon each other and the spout immersed in oil, release of the upper section permits the spring 22 to extend the sections, filling the chamber 75 24 and the connected chamber 40.

I claim:

1. An oiler comprising telescopic sections, a piston arranged in one of said sections and attached to another of said sections, a spout 80 for said oiler, and a valve controlled passage through said piston into said spout.

2. An oiler comprising telescopic sections, a piston arranged in one of said sections, means for securing said piston to another of 85 said sections, said means having a passage therethrough, and a valve operated by the movement of said piston and attached section for controlling said passage.

3. An oiler comprising a casing section, a 90 piston arranged in said section, a tube terminating in a spout connected to said piston, a valve seat disposed in said tube, and a valve adapted to engage said seat to close the passage through said tube affixed to said 95 casing section.

4. An oiler comprising a lower casing section, a piston arranged in said section, a tube terminating in a spout connected to said piston, a valve seat disposed in said tube, a 100 valve adapted to engage said seat to close the passage through said tube affixed to said lower section, and an upper casing section fixed on said tube and telescoped upon said lower section. 105

5. An oiler comprising a lower casing section, a piston arranged in said section, a tube terminating in a spout connected to said piston, a valve seat disposed in said tube, a valve adapted to engage said seat to 110 close the passage through said tube affixed to said lower section, an upper casing section fixed on said tube and telescoped upon said lower section, and a spring interposed between said lower and upper casing sections. 115

6. An oiler comprising a lower casing section, a piston arranged in said section, a tube terminating in a spout connected to said piston, a valve seat disposed in said 120 tube, a valve adapted to engage said seat to close the passage through said tube affixed to said lower section, an upper casing section fixed on said tube and telescoped upon said lower section, and an intermediate casing section interposed between said lower and upper casing sections. 125

7. An oiler comprising a lower casing section, a piston arranged in said section, a tube terminating in a spout connected to 130

said piston, a valve seat disposed in said tube, a valve adapted to engage said seat to close the passage through said tube affixed to said lower section, an upper casing section fixed on said tube and telescoped upon said lower section, an intermediate casing section telescoped between said lower and upper casing sections, and means for resisting the telescoping of said sections upon each other.

8. An oiler comprising a lower casing section, a piston arranged in said section, a tube terminating in a spout connected to said piston, a valve seat disposed in said tube, a valve adapted to engage said seat to close the passage through said tube affixed to said lower section, an upper casing section fixed on said tube and telescoped upon said lower section, an intermediate casing section telescoped between said lower and upper casing sections, a spring interposed between said lower and upper sections, and a spring interposed between said upper and intermediate sections.

25 9. An oiler comprising a lower casing section, a piston arranged in said section, a tube terminating in a spout and connected to said piston, an annular valve seat disposed in said tube, a rod affixed to said lower section extending through said valve seat into said tube, a valve on said rod adapted to engage said seat to close the passage therethrough, an upper casing section fixed on said tube and telescoped upon said lower section, and a spring interposed between said upper and lower sections.

10. An oiler comprising a lower casing section, a piston arranged in said section, a tube terminating in a spout and connected to said piston, an annular valve seat disposed in said tube, an upper casing section fixed on said tube and telescoped upon said lower section, a rod affixed to said lower section extending through said valve seat into said tube, a valve on said rod adapted to engage said seat to close the passage therethrough and to limit the extension of said upper section upon said lower section, and a spring interposed between said up-

per and lower sections and tending to cause 50 their extension one from the other.

11. An oiler comprising a lower casing section, a piston arranged in said section, a tube terminating in a spout connected to said piston, a valve seat disposed in said tube, a valve adapted to engage said seat to close the passage through said tube and to limit the upward movement of said piston in said lower section, an upper casing section fixed on said tube and telescoped upon said lower section, and a compression 60 spring interposed between said lower and upper section.

12. An oiler comprising a lower casing section, a piston arranged in said section, a tube terminating in a spout connected to said piston, a valve seat disposed in said tube, a valve adapted to engage said seat to close the passage through said tube and to limit the upward movement of said piston in said lower section, an upper casing section fixed on said tube and telescoped upon said lower section, an intermediate casing section interposed between said lower and upper sections, means tending to extend said upper section from the intermediate and from the lower sections, and means for limiting the extension of said upper section from said intermediate section.

13. An oiler comprising a casing formed of telescopic sections, a piston in one of said sections connected to and movable with another of said sections, said piston forming with the section in which it lies an oil chamber, means providing an inlet and outlet passage into said chamber, a valve controlling said passage operated by the relative movement between two of said sections, means for extending said telescopic sections 85 and means for limiting said extension.

In testimony whereof, I have hereunto set my hand at Oakland, California, this 25th day of May, 1918.

FORREST L. CANTRALL.
